(57) **CLAIM**

An ornamental design for a neck shade with built-in fan, as shown and described.

DESCRIPTION

FIG. 1 is a frontal perspective view of the neck shade with built-in fan showing my new design.

FIG. 2 is a top plan view of the design of FIG. 1.

FIG. 3 is a frontal elevation view of the design of FIG. 1.

FIG. 4 is a back elevation view of the design of FIG. 1.

FIG. 5 is a left-side elevation view of the design of FIG. 1.

FIG. 6 is a right-side elevation view of the design of FIG. 1.

FIG. 7 is a bottom plan view of the design of FIG. 1; and, FIG. 8 is a left-side frontal perspective view of the design of FIG. 1.

The broken lines shown in the drawings illustrate the environment in which the design is used and form no part of the claim.

The crosshatched pattern, although shown intermittently, is meant to represent fabric, and is understood to be distributed uniformly over the surfaces of the claimed design upon which it occurs.
